UNITED STATES PATENT OFFICE.

JAMES A. CLIFT, OF SPRINGFIELD, MISSOURI, ASSIGNOR OF ONE-HALF TO WAYNE E. BISHOP, OF SPRINGFIELD, MISSOURI.

ANGLE COCK.

Application filed March 30, 1926. Serial No. 98,564.

This invention relates to an angle cock for use in connection with fluid pressure air brake systems for railway rolling stock, and has for its object to provide, in a manner as hereinafter set forth, a device of the class referred to for reducing the pressure of air on the air hose line to an extent, to prevent the separation of the sections of the hose line, to overcome the pulling of the train pipe section from under the car when it is desired to uncouple the hose line sections, to prevent the flying around of the hose line sections in a direction to injure a trainman during the uncoupling of the hose line sections, to overcome the blowing of cinders and dust into the face of a trainman when the hose line sections are uncoupled, to prevent the sticking of the brakes, and to readily indicate to the engineer that something is wrong with the brake system when an angle cock is closed under such conditions providing a safety appliance to avoid damage to equipment.

Further objects of the invention are to provide, in a manner as hereinafter set forth, an angle cock for the purpose referred to which is simple in its construction and arrangement, strong, durable, compact, thoroughly efficient in its use, conveniently operated, readily installed and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a longitudinal sectional view of an angle cock in accordance with this invention.

Figure 2 is a section on line 2—2, Figure 1.

Figure 3 is a section on line 3—3, Figure 1 and illustrating the angle cock in open position.

Figure 4 is a view similar to Figure 3 with the angle cock closed.

Referring to the drawings in detail 5 generally indicates the casing of the angle cock and which is of tubular form. The casing 5 includes a body portion 6 formed with a vertically disposed cylindrical opening 7 at the bottom thereof and the wall of said opening is threaded throughout. The body portion 6 is furthermore provided with a frusto-conical shaped chamber 8 which extends from the upper end of the opening 7 and opens at the top of the body portion 6. The chamber 8 is vertically disposed. The outer side of the body portion 6 is formed, centrally thereof, with a vertically disposed slot 9 which opens into the passage 8 and the inner side of the body portion 6, centrally thereof, is provided with a vertically disposed slot 10 which opens into the chamber 8. The slots 9 and 10 are substantially rectangular in contour, aligned with each other and are positioned centrally with respect to the chamber 8.

Arranged within the chamber 8 is a bushing 11 which corresponds in contour to the shape of the chamber 8 and is of the same height as the height of the latter. The bushing 11 at its upper end is flushed with the top of the body portion 6, and is maintained in position, within the body portion 6, by a closure plug 12 at the lower end of the chamber 8. The bushing 11 is formed with a pair of diametrically opposed slots 13, 14, which align respectively with the slots 9 and 10. The slots 13 and 14 are of the same contour, height and width as the slots 9 and 10.

The closure plug 12 consists of an annular body portion 15, peripherally threaded as at 16 for engagement with the threads of the wall of the opening 7. The body portion 15 is furthermore formed with an annular flange 17 which abuts against the bottom of the body portion 6 of the casing 5. Depending from the body portion 15 is a polygonal shaped extension 18 for the reception of a suitable tool for connecting and disconnecting the plug 12 to and from the lower end of the body portion 6 for the purpose of closing and opening the lower end of the chamber 8. The body portion 15 of the plug 12

has its inner end, when the plug 12 is secured to the casing 5, positioned to support the bushing 11 in the position as shown in Figure 1. The bottom edge of the bushing 11 seats on the inner end of the body portion 15 of the plug 12 when the latter is in closure position with respect to the chamber 8. The plug 12 is chambered and the chamber formed therein extends from the projection 18 and throughout the body portion 15. The chamber in the plug is referred to generally by the reference character 19 and consists of a flaring upper portion 20, a circular intermediate portion 21 and a semi-spherical lower portion 22. The top of the portion 22 is of less diameter than the diameter of the portion 21 thereby providing a seat 23 for a purpose to be presently referred to.

Extending through the bushing 11 is a plug valve referred to generally by the reference character 24 and which consists of a body portion formed of a tapered upper part 25 of circular cross section, an intermediate part 26 having a tapered outer periphery 27 and a vertically disposed plane inner periphery 28. The said intermediate part 26 is segmental in cross section. The plug valve further includes a tapered lower part 29 of circular cross section and which has depending from the bottom thereof a circular collar 30 which is inset with respect to the outer periphery of the said part 29. The bottom of the lower part 29 is formed with a pocket or recess 31 and the inner face of the collar 30 forms a continuation of the wall of the recess 31. The lower part 29 is formed with a centrally disposed vertically extending passage 32 which opens into the recess 31 at the top thereof and said recess 31 opens into the chamber 20. The lower corner 33 of the part 29 is positioned below the bottom edge of the bushing 11 and seats on the wall of the flaring portion 20 of the chamber 19. The collar 30 extends into the chamber 19. The outer face 27 of the intermediate part 26 forms a continuation of the outer face of the upper part 25 and the lower part 29 of the plug valve. The intermediate part 26 gradually decreases in width from the part 29 to the part 25 of the plug valve. Formed integral with the top of the upper part 25 of the plug valve is a polygonal extension 34, which is arranged exteriorly of the casing 5. Connected to the extension 34 is a shifting means, of known construction, for the plug valve and said means is indicated at 35. It is thought unnecessary to specifically describe this means as it is the shifting mechanism now employed for the plug valves of angle cocks.

Integral with and projecting from that side of the body portion 6 formed with the slot 10 is a cylindrical interiorly threaded extension 36 for connecting the angle cock 65 to the train line pipe section, not shown.

Projecting from that side of the body portion 6 provided with the slot 9 is a curved tubular, interiorly threaded extension 37 for connecting a section of the hose line with the angle cock. The hose line section is not shown.

Arranged within the body portion 19, mounted upon the seat 23 and extending into the pocket 31, as well as bearing against the part 29 of the plug valve, is a coiled spring 38 which normally acts to maintain the plug valve in engagement with the inner face of the bushing 11 in a snug-like manner, but not to prevent the shifting of the plug valve to open and closed positions when occasion requires.

The body portion 6, of the casing 5, is formed with an inclined port 39 which opens into the atmosphere and is positioned in one of the non-slotted sides of said body portion 6 and is further arranged a substantial distance above the bottom of the body portion. It is the outer end of the port 39 which opens into the atmosphere and the inner end of said port registers with an inclined port 40 formed in the bushing 11 at a point in close proximity, but below, of the transverse median of the bushing 11. The outer end of the port 40 registers with the inner end of the port 39 and the inner end of the port 40 opens into the chamber 8. The port 40 extends in the same plane as the port 39. The ports 39 and 40 incline downwardly with respect to the vertical axis of the body portion 6. The ports 39 and 40 are provided for reducing the pressure of air on the air hose line to an extent to prevent the separation of the sections of the hose line, to overcome the pulling of the train pipe section from under the car during the uncoupling of the hose line sections, to prevent the flying around of the hose sections in the direction to injure a trainman, to overcome the blowing of cinders and dust into the face of the trainman when uncoupling the hose line sections, to prevent the sticking of the brakes, and to readily indicate to the engineer that something is wrong with the brake system when the angle cock is closed, under such conditions providing a safety appliance to avoid damage to equipment. When the plug valve is in open position, as shown in Figure 3, for the purpose of establishing communication between the train pipe section and a hose line section, the intermediate part 26 of the plug valve closes the port 40, see Figure 3, but when the valve plug is in position to shut off communication between the train pipe section and the hose line sections the port 40 is opened to the large passage 39' formed in the plug valve due to the manner of setting up the parts 25, 26 and 29 with respect to each other. When the port 40 is opened to

What I claim is:—

1. An angle cock comprising a casing provided with a valve chamber and having an inlet and an outlet, a bushing arranged in said chamber and provided with slots registering with said inlet and outlet, said casing and bushing having registering ports for establishing communication between said chamber and the atmosphere, said ports positioned above the bottom of the bushing and casing, a shiftable plug valve mounted in said bushing and having one side thereof cut away to provide a passage formed of a top, side and a bottom wall, said valve further constructed and arranged in connection with said passage for establishing communication between said inlet and outlet, for independently closing said outlet, for closing said ports to said chamber and for establishing communication between the outlet and said ports when the inlet is closed, said casing further provided with a pressure receiving chamber below said valve, and said valve provided with an opening for establishing communication between said passage and said pressure receiving chamber.

2. An angle cock comprising a casing provided with a valve chamber and having an inlet and an outlet, a bushing arranged in said chamber and provided with slots registering with said inlet and outlet, said casing and bushing having registering ports for establishing communication between said chamber and the atmosphere, said ports positioned above the bottom of the bushing and casing, a shiftable plug valve mounted in said bushing and having one side thereof cut away to provide a passage formed of a top, side and a bottom wall, said valve further constructed and arranged in connection with said passage for establishing communication between said inlet and outlet, for independently closing said outlet, for closing said ports to said chamber and for establishing communication between the outlet and said ports when the inlet is closed, said casing further provided with a pressure receiving chamber below said valve, said valve provided with an opening for establishing communication between said passage and said pressure receiving chamber, and said ports inclining downwardly towards the outer face of said casing and further extending in the same inclined plane throughout.

3. In an angle cock for the purpose referred to a plug valve comprising a one piece body portion formed of a tapered upper part of circular cross section, an intermediate part of segmental cross section, a tapered lower part of circular cross section and of greater diameter throughout than said upper part, said intermediate part having its outer periphery tapered to form a continuation of the periphery of said upper

the passage 39' the air or pressure in the hose line section will be reduced, due to the fact that the air will escape to the atmosphere, as indicated by the arrow shown in Figure 4. The intermediate part 26 of the plug valve is not only employed for closing the port 40 and the passage 39, but is also employed for shutting off communication between the train pipe section and a hose line section. The passage 39', formed in the plug valve, is of greater height and width than either of the slots 9, 10, 13 and 14. The top wall 40' of the passage 39' is positioned below the top wall of one of the aforesaid slots and the bottom wall 41' of the passage 39' is positioned below the bottom of any one of the aforesaid slots. The enlarged size of the passage 39' provides for the free passage of air from the slot 14 to the slot 13 and furthermore provides for the free passage of air from the hose line section to the port 40 when the latter is open. The opening 32 in the part 29 of the plug valve provides for the passage of air into the chamber 19 so that the pressure thereof will tend to snugly cause an engagement of the plug valve with the inner face of the bushing. The chamber 8 in the casing 5 is termed a valve chamber. The slots 10 and 14 an inlet for said chamber and the slots 9 and 13 an outlet for said chamber. The registering ports 39 and 40 are termed a pusher reducing passage leading from the valve chamber to the atmosphere. Owing to the manner of positioning the part 25 of the valve plug so that its lower end will extend below the top of the inlet and outlet for the valve chamber, the lower portion of said part 25, in connection with the intermediate part 26 acts as a means for opening and closing communication between the train line section and the hose line sections. When the valve is in the position as shown in Figure 4, the pressure in the hose line sections is reduced to the desired extent to perform the functions hereinbefore referred to.

Although an angle cock, in accordance with this invention, is designed primarily for use in connection with fluid pressure air brake systems for railway rolling stock, yet it is to be understood that the angle cock can be employed in connection with steam heating systems for railway trains, or for any other purposes for which it is found applicable.

It is thought that the many advantages of an angle cock, in accordance with this invention, can be readily understood, and although the preferred embodiment of the invention is as illustrated and described, yet it is to be understood that changes in the details of construction can be had which will fall within the scope of the invention as claimed.

and lower parts, said upper, lower and intermediate parts providing said body portion with an enlarged passage formed with a top, a bottom and an inner wall, said intermediate part gradually decreasing in width from its lower end to its upper end, said lower part provided with a pocket in

its bottom and further provided with a vertical opening for establishing communication between said passage and said pocket. 10
In testimony whereof, I affix my signature hereto.

JAMES A. CLIFT.
